SIGN

Mary T. Longley, Northbrook, Ill., assignor to The Hopp Press, Inc., New York, N.Y., a corporation of New York

Filed June 6, 1969, Ser. No. 17,556

Term of patent 14 years

Int. Cl. D20—03
U.S. Cl. D96—12

FIG. 1 is a front elevational view of a sign showing my new design, the rear being the same as the front shown;

FIG. 2 is an end elevational view thereof, the suspended panels and chains being omitted for convenience of illustration;

FIG. 3 is a top plan view thereof; and

FIG. 4 is a sectional view taken along the line 4—4 in the direction of the arrows in FIG. 2.

I claim:

The ornamental design for a sign, as shown and described.
